UNITED STATES PATENT OFFICE.

FREDERICK W. CHRISWELL, OF SEATTLE, WASHINGTON, ASSIGNOR TO PACIFIC CAR AN FOUNDRY COMPANY, OF SEATTLE, WASHINGTON, A CORPORATION OF WASHINGTON.

LOGGING CAR.

Application filed August 10, 1922. Serial No. 580,881.

To all whom it may concern:

Be it known that I, FREDERICK W. CHRISWELL, a citizen of the United States of America, and resident of the city of Seattle, in 5 the county of King and State of Washington, have invented certain new and useful Improvements in Logging Cars, of which the following is a specification.

My invention relates particularly to logging cars such as are shown in my previous 10 Patent No. 995,056, dated June 13, 1911, or in the patent to H. C. Jarvis, No. 1,415,357, dated May 9, 1922.

Cars of the type referred to are known to 15 the trade as connected-truck cars and are used for carrying logs. For this purpose they are very efficient. They are characterized by a body framing which consists mainly of a central back bone composed of 20 heavy timbers or sills secured together, this extending at each end beyond the bunk and bolster and carrying the car coupling and draft mechanism.

To provide room for draft rigging the 25 central timber or sill is cut short and the draft rigging secured in the space thus provided between the two outer sills or timbers. In loading logs it is unavoidable that logs are occasionally dropped upon the projecting 30 ends of these central timbers, which sometimes breaks them outwardly of the bolsters. It is one of the chief objects of my invention to provide a type of construction which will materially strengthen this part 35 of the back bone and prevent its being accidentally broken in the manner referred to.

My invention comprises those novel parts and combinations thereof which are shown in the accompanying drawings, described in 40 the specification, and particularly defined by the claims terminating the same.

In the accompanying drawings I have shown my invention in the form which is now preferred by me.

45 Figure 1 is a plan view of an end of such a car, including my invention therein.

Figure 2 is a transverse section through the car near the coupling device.

I have illustrated the sill at 1 in the drawings and the transverse bunk at one end thereof at 2. The bunk illustrated is pivoted in the sill, by means of the pin 11, but may be fixed thereto as in my previous patent referred to. I have not illustrated

trucks, inasmuch as these form no part of 55 the present invention. The pin illustrated at 11, however, may be extended to form a king pin by means of which the truck may be secured beneath the sill 1. The coupling means which I have illustrated at 3 may be 60 of any approved or suitable type, the particular construction thereof forming no part of this invention. This is shown as supported in the end of the sill 1 outwardly of the bunk 2.

In the former constructions the coupling 3 was connected directly to the end of the sill 1 and whenever this projecting end of the sill was broken off it left the car with no proper coupling means available for moving 70 it, thus causing a tie-up until proper repairs could be made, which was difficult, or until a temporary coupling means could be rigged up. I have provided a pair of reinforcing bars, illustrated as I-beams 4, which extend 75 from the end of the sill 1 to a point preferably inwardly of the bunk 2, but at least to this bunk and to a connection at that point to the car bolster. These I-beams I have shown as interposed between the edges of the 80 outer beams forming the sill which adjoin the central beam, the beams being suitably cut out to receive the I-beams 4. The whole sill is then secured together, as by means of tie bolts 41, to make a rigid and unitary construction. 85

In order to receive the coupling 3 I have shown the lower inner flanges of the I-beams cut away for a short distance as indicated at 90 42. The central beam of the sill is somewhat shorter than the two outer beams, and into the space thus provided between the I-beams 4 and between the end of the central beam of the sill and the ends of the two outer beams, I place the coupling 3, this being a 95 unitary member which can be inserted into place. This is secured in any suitable or ordinary manner, a plate 32 being shown for this purpose.

In this manner the projecting outer end 100 of the sill 1 is strengthened by a connection to a point inwardly of the bunk. Any load dropped upon this projecting end of the sill will react through the I-beams 4 upon the central portion of the sill 1 and consequently 105 the sill will be greatly strengthened. The coupling means may be conveniently inserted and secured in such a construction and if

damaged may be easily taken out and replaced. Even though the wooden beams of the sill were to be damaged—which is not likely—the car could be moved by the connection of the coupling 3 to the main body and running gear of the car, through the I-beams 4.

What I claim as my invention is:

1. In a logging car, a longitudinal sill comprising three parallel beams secured together, the central beam being shorter than the outer beams, a transverse bunk and bolster adjacent an end of said sill, an I-beam interposed between the central beam and each outer beam, and extending inward to the bunk and bolster and outward substantially to the sill end, and a coupling lying between and secured to said I-beams beyond the end of the short central beam.
2. In a logging car, a longitudinal sill including a pair of spaced I-beams, a load-supporting bunk secured upon said sill to straddle said I-beams, a portion of the inner flanges of said I-beams being cut away outwardly of said bunk, and a coupling receivable between said I-beams through the cut-away portion, and securable in said sill.
3. A car having a central back bone composed of three beams secured together, the central beam being shorter than the outer sills to provide recesses for the draft rigging, and reinforcing metal beams secured to

the inner faces of the outer beams and extending between said outer beams and the central beam.

35

4. In a logging car, a longitudinal central sill extending the entire length of the car underframe and containing three timbers secured alongside of each other, the center timber being enough shorter than the outer timbers to form a pocket at each end for the reception of a draft gear, a reinforcing I-beam secured against the inner faces of each outer timber and between the outer and center timbers from the outermost ends of the outer timbers to a point well inward of the bolster.

45

5. In a logging car, a longitudinal central sill extending the entire length of the car underframe and containing three timbers secured alongside of each other, the center timber being enough shorter than the outer timbers to form a pocket at each end for the reception of a draft gear, the central timber being of a length to extend well outwardly of the bolster, a reinforcing I-beam secured against the inner faces of each outer timber and between the outer and center timbers from the outermost ends of the outer timbers to a point well inward of the bolster.

50

Signed at Renton, King County, Washington, this 24th day of July, 1922.

FREDERICK W. CHRISWELL.
